UNITED STATES PATENT OFFICE.

WILLIAM L. R. EMMET, OF SCHENECTADY, NEW YORK, ASSIGNEE TO GENERAL ELECTRIC COMPANY, A CORPORATION OF NEW YORK.

GOVERNING MECHANISM FOR TURBINES.

No. 861,099.

Specification of Letters Patent.

Patented July 23, 1907.

Application filed March 17, 1906. Serial No. 306,503.

To all whom it may concern:

Be it known that I, WILLIAM L. R. EMMET, a citizen of the United States, residing at Schenectady, county of Schenectady, State of New York, have invented certain new and useful Improvements in Governing Mechanisms for Turbines, of which the following is a specification.

The present invention relates to governing mechanisms for turbines, more especially of the elastic-fluid type, wherein the valves controlling the passage of steam or other motive fluid through the discharging devices and buckets are mechanically actuated both in opening and closing in response to load changes.

The object of the invention is to improve the construction and operation of such mechanisms.

For an understanding of the scope and nature of my improvements, attention is directed to the accompanying description and claims appended thereto.

In the accompanying drawings, which illustrate one of the embodiments of my invention, Figure 1 is a partial side elevation of a turbine fitted with my improved governing mechanism; Fig. 2 is an end view thereof; Fig. 3 is a view in elevation of the valve-actuating mechanism with the casing therefor in section; Fig. 4 is a plan view of the same with the cover of the casing removed; Fig. 5 is a cross section of the valve-actuating mechanism; Fig. 6 is a perspective view of the cross-head and the valve actuators carried thereby; Fig. 7 is a perspective view of the mechanism used to shift the dogs which actuate the valves; Fig. 8 is a longitudinal section of the speed- or load-responsive device; and Fig. 9 is a perspective view of one of the valve-actuating dogs.

The invention is shown as applied to a multi-stage turbine of the Curtis type, but it is applicable to other types of turbines, as will be readily understood.

I have shown the mechanism in connection with admission valves only, but it can be used for operating the valves between stages, or for operating both the admission and stage valves. It is applicable also to single-stage turbines.

1 represents the turbine with the first stage partly in section to show one of the admission nozzles 2, which may be of the expanding or non-expanding type, 3 the wheel buckets and 4 the intermediate or stationary buckets, where such buckets are required, as for example, where the velocity of the steam or other motive fluid is abstracted by two or more operations in the same stage.

50 The admission of motive fluid to the nozzles, nozzle sections, or other fluid-discharging devices is controlled by valves 5 located in a valve chest that is bolted to the turbine. I may use as many of these valves as there are fluid-discharging devices, or a less number. In the

embodiment illustrated a plurality of these valves is 55 provided, but in its simplest form I may use only a single valve.

The rotary member of the turbine is mounted on a shaft 6 carried by suitable bearings 7, of which one is shown. On the end of the shaft is a speed-responsive device inclosed by a casing 8. The said device imparts movement to the means controlling the opening and closing of the valves by a horizontal lever 9 attached to a connecting rod 10, the latter being pivotally united to an arm 11 mounted on the upright spindle 12. On the upper end of the spindle is an arm 13, Figs. 1 and 2, connected to a horizontally disposed lever 14 pivoted at a point between its ends to the casing 15 that incloses the actuating mechanism. As the speed changes the upright spindle is rocked to and fro, causing the dogs to 70 engage or let go of the valve stems or attached cross-heads, as will appear later. The casing is suitably supported, as for example, by the posts or columns 16 attached to one of the main bearings.

The governing mechanism includes a vibrating lever 75 17 that is constantly in motion and which supplies the necessary power to open and close the valves one after the other or in any predetermined order. Motion is imparted to this lever by a vertically disposed connecting rod 18 receiving motion from a crank-pin 19, shown 80 in dotted lines, Fig. 1. The pin is mounted on a disk 20 driven by the worm wheel 21 meshing with a worm 22 on the main shaft. This relation of parts insures continuous vibratory action of the lever 17 when the machine is in operation, and also a practically unlimited amount of power. It is preferable to reduce the speed of the parts by gearing where the turbine runs at the speeds commonly employed. The crank disk 20 also furnishes the power for driving the plunger 23 of the lubricating pump 24, the latter being inclosed 90 in a casing 25 supported by the base of the turbine. By locating these parts between the bearing and the turbine proper, they are out of the way and also reduce the longitudinal dimension of the machine. Connected with the pump is a chamber 26 to reduce the pulsating effect of the plunger on the discharged lubricant. Fluid from the pump is discharged by the pipe 27 into the pipe 28 located in the base of the machine. This pipe extends longitudinally through one side of the base, then crosses over to the opposite side and extends 100 parallel to the first portion back to the left-hand end of the machine. Lubricant under pressure is admitted to the left-hand bearing by the pipe 29, a similar pipe being provided for the other bearing. In this pipe is a valve 30 for regulating and shutting off the supply. 105 The exhaust lubricant is returned from the bearing to the chambered casing inclosing the pump by the pipe 31. Between the pump and the air chamber 26 is a

check-valve 32 (Fig. 2) opening toward the chamber. On the discharge side of the pump is an adjustable relief valve 33 by means of which the discharge pressure can be regulated. The casing 25 is normally filled 5 with lubricant at atmospheric pressure, and the pump cylinder is filled by gravity through the opening 34, Fig. 1. The valve-actuating mechanism within the casing is lubricated by an oil cup 35 located on the cover, and lubricant is returned to the system by the 10 pipe 36 connected to a chamber in the bearing. The upper end of the pipe extends a certain distance into the casing so as to maintain a body of lubricant therein sufficient to lubricate the lower members. The arrangements of the ducts for lubricating the parts of the valve- 15 actuating mechanism will be described later.

I have chosen as an illustration of my invention a mechanism having five admission valves, but the number can be increased or decreased as desired. Since all of the valves are alike, the description will first be 20 directed specifically to one of them, and later to the means whereby the successive operation is attained.

Each valve is provided with a stem which is made in two parts 40 and 41, so that the actuating mechanism can be removed from the valve proper. Between the 25 two parts of the stem is a coupling 42. The portion of the stem directly attached to the valve is provided with an enlarged head which enters a head 43 on the other portion, the said head containing a downwardly opening slot 44, Fig. 6, through which the stem can be 30 slipped. By means of this arrangement the outer portion of the stem can be lifted bodily without disturbing the valve and its attached stem.

Extending longitudinally of the casing 15 is a main rock-shaft 45 and an auxiliary rock-shaft 46. The 35 former is rigidly attached to the vibrating lever 17 which is kept constantly in motion by the crank 19, Fig. 1. Motion from the main to the auxiliary rock-shaft is transmitted by the connecting-rod 47 located at the far end of the casing 15, Fig. 5. This rod connects the cranks 48 keyed or otherwise secured to the 40 shafts. Mounted on and guided by these two shafts and arranged to slide longitudinally thereof as the speed of the turbine changes, is a slide 49, Fig. 7, supported at four points and having projections 50 and 51 45 thereon to control the action of the double-ended dog 52 on the valve stem. The object in using an auxiliary rock-shaft is to overcome the static friction or friction of repose of the parts. I regard it as being a highly desirable arrangement because it reduces 50 the load on the shaft governor at starting and also increases its effectiveness, but under certain condition I may substitute therefor a non-moving guide.

Mounted in suitable fixed guides 53 and 54 in the casing and arranged to move constantly to-and-fro is a 55 cross-head 55 carrying the dogs 52, Figs. 5 and 9. Reciprocating motion is constantly imparted to the cross-head 55 from the rock-shaft 45 by means of the cranks 56 secured at opposite ends of the rock-shaft, and connecting rods 57 and 58. The object in using two cranks 60 and connecting-rods is to transmit motion and prevent binding of the parts. In certain cases, however, it is possible to use only one crank and connecting rod and locate them in a central position. The outer portion 41 of the valve stem passes through the casing 15 and is 65 located in guides in the cross-head, the latter being

capable of moving to and fro without disturbing it. To prevent the stem from turning and thus getting the actuating shoulders and the slot 44 in the coupling in other than a downward position, a pin 59, Fig. 5, mounted in the cross-head and arranged to move in 70 slot in the valve stem.

The dog 52 is pivoted centrally and has two working surfaces at opposite ends adapted to engage the shoulders 60 and 61 on the under side of the valve stem. It normally stands with one corner up and the other 75 down; it has no intermediate or central position. To insure this action taking place, extension springs 62 are provided which work over a dead center. In order to obtain an effective snap action with a minimum height of parts, the dog is provided on its under 80 side with a projection through which the pin 63 passes. To this pin are pivotally connected flat pieces 64 each having an enlarged hole to pass around the pivot of the dog, the upper end of each piece being connected to a tension spring 62. Other means can be employed to obtain 85 this snap-like action of the dog without departing from the spirit of my invention.

The slide or means 49 controlling the action of the projections 50 and 51 on the pivoted dog 52 is connected by the flat rod 65 with the lever 14 pivotally supported 90 on the outside of the casing 15. As the speed increases, the slide with its attached projections is moved outwardly thus causing the projection 51 to move under the incline surface at the end of the dog 52 at some portion of its stroke and raise the right-hand end, thus 95 permitting the next stroke of the cross-head 55 to the right to close the valve. Assuming that the load increases and the speed falls slightly, the reverse operation takes place, and the projection 50 moves under the left-hand end of the dog 52 and raises it a certain 100 amount, and the spring 62 snaps the dog into the position shown in Fig. 5, and the next outward stroke of the cross-head 55 opens a valve.

The projections 50 and 51 may be separated in the plane of the dog by a distance which is slightly greater 105 than the width of the dog measured in a plane at right angles to its length. In this event the dog can, at a definite speed of the turbine move to and fro without changing its position or the position of the valve. On the other hand, the projections may be so set that the 110 distance between them, measured in the plane of the dog, is less than the width of the dog, in which case the valve at the critical point in the regulation will, for a certain limited range of speed, open and close once for each stroke of the cross-head.

Owing to the fact that there are a number of joints in the connection between the speed governor and the slide 49, containing more or less play, especially as the parts become worn, it is desirable to compensate therefor and eliminate the effect of said looseness as much as 120 possible. To do this a spring 66, shown in dotted lines, Fig. 3, is attached to the slide 49, and to a fixed abutment 67 on the casing 15. The spring should be of such a length and character as to exert a substantially uniform tension on the slide irrespective of its position. 125 Other means for accomplishing this can be provided.

It now remains to describe how the successive action of the valves both in opening and closing is accomplished. On the upper side of the slide are as many pairs of dog-controlling projections as there are valve 130

stems, the said projections being arranged in two rows. The pitch of the projections in a given row differs from that of the dogs 52 by such an amount as will cause, on an increasing load, first one projection to tilt a dog to 5 the position shown in Fig. 5 and permit the cross-head to open one valve and then another, and so on until all the valves are open. Upon a decreasing load the reverse action takes place and the projections in the other row will act on the dogs one after the other and permit 10 the cross-head to close the valves successively. The relation of the rows of projections to the dogs is best shown in plan in Fig. 4. The difference in position of two pairs of projections and their coöperating dogs will best be seen by looking at the dogs at opposite ends 15 of the slide. Under normal conditions certain of the valves will be closed, certain of them open, and at least one valve will be opening and closing frequently to admit pulsations of steam or other motive fluid from the valve chest to the fluid-discharging nozzle or other 20 device. It will readily be understood that a given number of open nozzles will seldom exactly satisfy the load conditions, while a number greater by one than said number will supply too much, hence one valve will act as described and in so doing admit fluid in pulsations to the turbine. 25

As a refinement of the invention, the dogs and projections may be so related that the valve at the critical point in the regulation will open and close once for each 30 stroke of the vibrating lever 17. This means that the distance between the dogs of a pair, measured in parallel planes extending longitudinally of a dog, is less than the width of a dog.

Referring to Fig. 8, 67 and 68 represent the weights of the speed governor each of which is provided with a 35 hardened steel plate 69 having inner and outer shoulered portions adapted to receive the hardened knife edges 70 and 71. The knife edges 70 are carried by links 72, the opposite ends of which are pivotally united to the movable abutment 73. Secured to the abutment by a bolt is a nut 74 having an external thread arranged to receive and retain one end of the weight-opposing spring 75. The inner end of the spring is similarly provided with an externally threaded nut 77. The nut is also interiorly threaded to receive the adjusting bolt 78. The bolt is seated in a shell 79, that is 40 removably secured in the recessed end of the bucket wheel shaft 80. The shell is retained by a nut 81 to which the casing 8 is attached. The shell is slotted at suitable points, usually three or four, to receive rollers 50 82 for guiding the movable abutment and reducing the friction. Connected to the abutment is a rod 83 having a head at its outer end acting through one or more ball bearings on a hardened steel plate 84, the latter being mounted in a head 85 which is connected to the lever 9 55 by a link 86. The lever is pivotally supported in an openwork frame 87 that is bolted to the end of the bearing 7. The lever 9 is guided in its movements by a guide 88 on its under side.

With a valve gear of this character it is important to 60 keep the parts well lubricated. With this end in view the oil cup 35 is mounted on the removable cover of the casing 15 and the lubricant therefrom drips into the tray formed in the upper side of the cross-head 55. In the tray are small oil-carrying passages 90 leading to the 65 guides in the cross-head for the stems 41. The excess

lubricant flows over the surface of the stem and lubricates the upper surface of the dogs 52 and also the pivot 91 therefor, which in the present instance is common to all of the dogs. Passages 92 are also provided to lubricate the connecting-rods 57 and 58 and the attached 70 cranks. As previously stated, the drain-pipe 36 leading from the casing 15 to the bearing 7 projects into the former by an amount sufficient to maintain a body of oil at about the level of the axis of the main rock-shaft; this will abundantly lubricate the remaining elements, 75 especially as the movements of the cross-head will tend to agitate the oil more or less.

One of the very important features of a valve gear is to arrange the parts so that they are readily accessible; this has been done with the construction shown. The 80 valves are located in a chest that is detachably secured to the turbine and the actuators therefor in a casing supported by the bearing and having a removable cover to expose the parts. The cross-head is arranged to move bodily toward and away from the turbine with a definite number of strokes per minute, while the slide 49 carrying the projections governing the action of the dogs 52 is free to move to and fro in a longitudinal direction under the control of the speed governor, the direction of motion of the slide being at right angles to that of the 85 cross-head 55. When it is desired for any reason to take down the mechanism, the cover of the casing 15 is removed, thus exposing the cross-head. The screws for the cross-head guides 53 and 54 are removed, the connection broken between the rod 65 and the speed-actuated mechanism, and the pivots connecting the cross-heads and the connecting-rods 57 and 58. The cross-head can then be raised to disengage the parts of the valve stem and then moved longitudinally to withdraw the bar or rod 65. This exposes all of the dogs and the 90 adjacent parts. The slide 49 can then be removed by raising it bodily. The remainder of the mechanism will then be accessible, as readily understood.

In accordance with the provisions of the patent statutes, I have described the principle of operation of my 105 invention together with the apparatus which I now consider to represent the best embodiment thereof; but I desire to have it understood that the apparatus shown is only illustrative and that the invention can be carried out by other means. 110

What I claim as new and desire to secure by Letters Patent of the United States, is,

1. In a governing mechanism, the combination of a valve, a cross-head which is constantly reciprocated in a given path for opening and closing the valve, a means moving in a plane at an angle to the direction of motion of the cross-head for controlling the action thereof on the valve, and a device responsive to load changes for shifting said means. 115

2. In a governing mechanism, the combination of a 120 valve, a cross-head which is reciprocated in a given path, a dog carried by the cross-head for opening and closing the valve, a means moving in a plane at right-angles to the direction of motion of the cross-head for moving the dog in a manner to cause it to operate the valve, and a 125 load-responsive device for shifting the said means.

3. In a governing mechanism, the combination of a valve, a means which is reciprocated in a given path, a double-acting pivoted dog carried by the means for operating the valve, a device for snapping the dog first into one 130 of its positions and then the other, and a means responsive to load variations for controlling the action of the dog.

4. In a governing mechanism, the combination of a valve, a means which is reciprocated in a given path, a double-acting pivoted dog carried by the means for operating the valve, a spring working over a dead center for snapping the dog first into one of its positions and then the other, and a speed-responsive device for tilting the dog in one direction or the other as the load conditions change. sets to cause the said means to open and close the valves successively. 75
5. In a governing mechanism, the combination of a valve, an actuator, a double-ended pivoted dog carried by the actuator adapted to engage the valve stem and move it, a slide for causing one end or the other of the dog to engage the stem, and a speed-responsive device for moving the slide. 10
6. In a governing mechanism, the combination of a valve having a stem, a cross-head through which the stem freely passes, a means for reciprocating the cross-head without moving the valve, a dog carried by the cross-head which is adapted to engage with and move the valve, and pins moving in response to speed changes for causing the dog to actuate the valve. 15
7. In a governing mechanism, the combination of a valve having a stem, a cross-head, a guide therefor, a rock-shaft, a connection between the rock-shaft and the cross-head for transmitting motion, a valve stem, and a means carried by the cross-head and acting in response to load changes for opening and closing the valve. 20
8. In a governing mechanism, the combination of a valve having a stem, a cross-head, a guide therefor, a means for transmitting motion from the cross-head to the valve, a slide moving at an angle to the path of movement of the cross-head, a guide therefor, a device carried by the slide for controlling the said means, and a speed-responsive device connected to and moving the slide. 25
9. In a governing mechanism, the combination of a valve, a means for opening and closing the valve, a device for controlling the action of the said means in response to load changes, and a support for the said device which is normally in motion to prevent the friction of repose. 30
10. In a governing mechanism, the combination of a valve, a means for opening and closing the valve, a device for controlling the action of the said means in response to load changes, a guide for said device having parallel surfaces, and means for keeping the guide in motion to prevent the friction of repose. 35
11. In a governing mechanism, the combination of a valve, a means for opening and closing the valve, a device for controlling the action of the said means in response to load changes, a pair of connected rock-shafts which form a guide for the said device, and a driving means for rocking the shafts. 40
12. In a governing mechanism, the combination of a valve, a means for opening and closing it, a device governing the action of said means, a speed governor connected to the device, and a means for taking up the play of the parts. 45
13. In a governing mechanism, the combination of a valve, a means for opening and closing it, a device governing the action of said means, a speed governor connected to the device, and a spring for taking up the play in the connection between the governor and said device. 50
14. In a governing mechanism, the combination of a plurality of valves, a cross-head which is common thereto means carried by the cross-head for actuating the valves, a slide arranged to move to and fro at right angles to the plane of movement of the cross-head in response to load changes, and pins or projections on the slide for controlling the action of said means. 55
15. In a governing mechanism, the combination of a plurality of valves, a cross-head which is common thereto, means carried by the cross-head for actuating the valves, a slide arranged to move to and fro at right angles to the plane of movement of the cross-head in response to load changes, and pins or projections on the slide arranged in 60
- sets to cause the said means to open and close the valves successively. 75
16. In a governing mechanism, the combination of a plurality of valves, a cross-head, a rock-shaft, cranks and rods driven by the shaft and connected to opposite ends of the cross-head for reciprocating it, dogs carried by the cross-head for actuating the valves, and a speed-responsive device for controlling the action of the dogs. 80
17. In a governing mechanism, the combination of a plurality of valves, a cross-head, a rock-shaft, cranks and rods driven by the shaft and connected to opposite ends of the cross-head for reciprocating it, dogs carried by the cross-head for actuating the valves, a slide arranged to move at right angles to the plane of movement of the cross-head, means on the slide for controlling the dogs, and a speed-responsive device connected to and moving the slide. 85
18. In a governing mechanism, the combination of a valve, a two-part stem therefor, a coupling between the parts of the stem, a reciprocating cross-head, a means carried by the cross-head which acts through one part of the stem to open and close the valve, and a speed-responsive device controlling the action of said means. 90
19. In a governing mechanism, the combination of a casing, a plurality of valves, a removable cross-head located in the casing, and dogs mounted on and removable with the cross-head for actuating the valves. 95
20. In a governing mechanism, the combination of a casing, a plurality of valves, a double-acting dog for actuating each of the valves, a spring for causing each dog to snap from one position to another, and a removable cross-head located in the casing to which the dogs and springs are attached and removable therewith. 100
21. In a governing mechanism, the combination of a casing, a plurality of valves, actuators therefor, a cross-head for moving the actuators, and a receptacle or tray in the cross-head for supplying lubricant to the actuators. 110
22. In a governing mechanism, the combination of a cross-head, a plurality of valves, actuators therefor carried by the cross-head, a slide arranged to move to and fro, and a four-point support for the slide. 115
23. In a governing mechanism, the combination of a regulator, a tilting dog that moves to and fro and when in one position moves the regulator in one direction and when in the other of its positions moves the regulator in the opposite direction, and a governor for controlling the action of the dog. 120
24. In a governing mechanism the combination of a plurality of regulators, a plurality of dogs for moving the regulators in one direction or the other, a sliding cross-head forming a support common to dogs, and a governor for controlling the dogs. 125
25. In a governing mechanism, the combination of a valve, a stem therefor having shoulders, a tilting dog pivotally supported at one side of and at a point between the shoulders, a means for moving the pivot of the dog to and fro, and a device responsive to load changes for causing one end of the dog or the other to engage a shoulder on the stem and move the valve. 130
26. In a governing mechanism, the combination of a valve, a stem therefor having opposing shoulders, a guide for the stem, a means for preventing the stem from turning, a double acting tilting dog situated on the side of the stem adjacent the shoulders, an actuator for the dog, and a governor for controlling the action of the dog on the shoulders. 135

In witness whereof I have hereunto set my hand this 140
16th day of March, 1906.

WILLIAM L. R. EMMET.
